a corporation of New York

Application June 4, 1935, Serial No. 57,129

Term of patent 7 years

To all whom it may concern:

Be it known that I, Fred Schofer, a citizen of the United States, residing at New York, in the county of New York and State of New York, have invented a new, original, and ornamental Design for a Target Aeroplane for Amusement Devices, of which the following is a specification, reference being had to the accompanying drawing, forming part thereof.

In the drawing:

Fig. 1 is a top plan view of a target aeroplane for amusement devices, showing my new design.

Fig. 2 is a side elevation thereof.

Fig. 3 is a front view thereof.

I claim:

The ornamental design for a target aeroplane for amusement devices, as shown.

FRED SCHOFER.
